2. DESIGN FOR A STOVE BY S. WILLIAMS

Williams. One of a pair of door panels. *Original drawing* done for me.

Original drawing done for me.

Williams, Bird & C° Ass'ees of
Seth Williams Jr. of Nashua, N. H.
Letters Patent N° 365 Dated April 8, 1851.

The Schedule referred to in these Letters Patent and making part of the same.

To all Persons to whom these Presents shall come:

Be it known, that
I, Seth Williams Jr. of Nashua, in the County of Hillsborough & State
of New Hampshire, have invented or produced, a new and useful design for a
Cooking Stove, and I do hereby declare that the same is fully described & repre-
sented in the following Specification and accompanying drawings, letters
figures and references thereof.

Of the said drawings, figure 1 represents a
side elevation of the Stove. Figure 2 a front elevation of it, and figure 3 a
section of the side plate, exhibiting the projections of the cornice and base; the
said section being taken vertically, and through the middle of the front upper
door of the side.

The combination of elements composing the design in both the front or both of the side plates, is the same.

The ornamental design of each plate consists of the peculiar ornamental base A - the peculiar ornamental pilasters B, B, &c. and the cornice C, etc.

The front plate has four pilasters B, B, B, B, while the side plate has only three; the ornamental design of the base, shaft and capital of each pilaster, being essentially the same. The ornamental design of each foot, on its two sides, will be readily seen, by inspection of figures 1&2, it being the same ornamental design which composes the bases.

The ornamental design of each of the doors E, F, G, H, and I, as well as the mere representations K, L, of doors, may be said to be essentially the same; the only difference being in the number of their central, four-pointed, star ornaments, and the size of the bases from which said star ornaments are projected.

The bas-relief design of the central part of each door, or the representation of a door, consists of one or more star ornaments a, a, a, projecting in relief, from a square or rectangular projection b, also the said projecting part b, and the four plumed leaves c, c, c, extended from the corners of the projection b, as seen in the drawings.

I claim as my invention, or production, the ornamental design, essentially as described and represented in the drawings.

In testimony whereof, I have hereto set my signature this twenty eighth day of September, A.D. 1850.
